PRESS FOR PROPELLER BLADE SECTIONS

Frederick A. Gruetjen, Milwaukee, Wis., assignor
to A. O. Smith Corporation, Milwaukee, Wis.,
a corporation of New York

Application August 14, 1944, Serial No. 549,466

6 Claims. (Cl. 113—48)

1

This invention relates to a press for propeller blade sections and the like, wherein a tubular blank is flattened to blade shape.

The principal object of the invention is to provide a press in which the blank is expanded in one diametrical direction while it is being contracted in a diametrical direction at substantially right angles to the first.

Another object of the invention is to provide such a press wherein both the expansion and contraction are obtained from a single relative motion of the press platens.

Another object is to provide a simple and efficient expanding mandrel operated by the platen movement of a press to expand a blank in the dies.

Other objects and advantages will be set forth hereinafter in connection with the description of an embodiment of the invention illustrated in the accompanying drawings.

In the drawings:

Figure 1 is a side elevation of the press;

Fig. 2 is a right-hand end elevation of the press;

Fig. 3 is a left-hand end elevation of the press;

Fig. 4 is a transverse vertical section taken on line 4—4 of Fig. 1;

Fig. 5 is a horizontal section taken on line 5—5 of Fig. 1;

Fig. 6 is a central longitudinal vertical section taken on line 6—6 of Fig. 5 with the dies open;

Fig. 7 is a similar section showing the dies closed and mandrel expanded; and

Fig. 8 is a top plan view of the press with the upper platen and die operating cams removed.

The press comprises a compact die unit 1 that can be secured to the platens 2 and 3 of any suitable power actuator such as the hydraulic press mechanism 4.

The unit 1 constitutes the important part of the invention and comprises a base plate 5 adapted to be supported upon the lower fixed platen 2 of the press, and an upper punch member 6 having a flat top adapted to be secured to the upper platen 3 of the press.

The dies 7 and 8 extend longitudinally of the unit and are adapted to move laterally toward and away from one another. The dies 7 and 8 rest upon wear plates 9 set in a recess in base plate 5 and a T-member 10 secured to the base plate 5 has its head riding in a similarly shaped slot in the dies and interlocked therewith to hold the dies in alignment.

The inner faces of the dies 7 and 8 are recessed for receiving and forming the blank 11 which in the illustration may constitute a tubular tip sec-

2

tion for a propeller blade having leading and trailing edge fins 12 extending in a slight spiral in the blank to correspond with the twist of the blade.

The outer side faces of the dies 7 and 8 are slanting at an angle from the perpendicular and have wear plates 13 secured thereto. The punch member 6 has downwardly depending side members 14 which have their inner faces slanting in a complementary manner to the slanting sides of the dies and located to effect movement of the dies toward one another by a wedging action when the punch is forced downwardly in engagement with the wear plates 13.

The dies 7 and 8 are held outwardly against the slanting surfaces of the punch by means of a pair of springs 15 on each side. The springs are mounted on stud bolts 16 secured in the die members at opposite ends of the punch side members 14 and passing through openings in the respective upstanding posts 17 on the baseplate. Each bolt 16 is adapted to reciprocate through the opening in the respective stationary post 17 and carries a coil spring 15 disposed between the head of the bolt and the post biasing the respective die member outwardly.

Wear plates 18 are secured to the outer sides of the punch side members 14 and engage the inner surfaces of the stationary posts to guide the punch in its downward movement and prevent deflection of the side members 14.

In the flattening of a tip section 11, it is preferred to expand the blank in one direction as it is flattened in the other. For this purpose the present invention provides an expanding mandrel 19 comprising a central longitudinally tapered wedge member 20 connected by a longitudinal T-slot interlock to an upper edge 21 and to a lower edge 22, the edges 21 and 22 being shaped to engage the blank throughout its length at the root of the fins 12, and the entire mandrel being shaped to correspond with the internal shape of the blank upon completion of the flattening operation.

The central wedge member 20 is forced longitudinally between edges 21 and 22 as the punch 6 is lowered. This is accomplished by securing an upright guide 23 to the base 5 at the rear end of the dies 7 and 8, and spaced therefrom. The guide 23 has a slanting cam surface 24 at the bottom of a groove 25 in its face toward the dies. Plates 26 secured to the upright 23 partially close the groove 25 to form it into a T-slot. A pivot block 27 rides up and down in the groove 25 and has a link 28 pivoted thereto and to a bracket 29 secured to the underside of the flat top of punch 6. Another link 30 is pivoted to block 27 and to

the end of wedge member 20. Movement of punch 6 up and down effects sliding of block 27 along cam surface 24 in stationary grooves 25 and thereby effects outward and inward movement of wedge member 20 in mandrel 19. Shims 31 may be placed between bracket 29 and punch 6 and serve to provide for adjustment of the movement and position of wedge member 20 relative to the dies 7 and 8.

Movement of the blank 11 and of the edges 21 and 22 longitudinally during forming is prevented by the tie bar 32 extending across the top of the two posts 17 to the rear of the dies 7 and 8. A similar tie bar 33 extends across the top of the two posts 17 at the front end of the dies 7 and 8. The tie bar 32 engages the end of the blank and also of the dies 7 and 8 and serves to hold them in alignment. Flanges 34 on the rear ends of mandrel edges 21 and 22 also engage the dies to hold the edges against forward movement when wedge member 20 is forced forwardly therebetween. A cover plate 35 is secured to the posts 17 at the rear and prevents rearward movement of mandrel edges 21 and 22 while allowing the edges to move apart to effect the spreading of the blank in a vertical direction. The shank of member 20 rides in a guideway 36 in plate 35 which supports the mandrel horizontally.

The apparatus is loaded and unloaded at the front end where a trap door arrangement secures the blank in place during forming. The trap door 37 is hinged along its bottom edge to the base plate 5 to pivot between an open horizontal position for loading the dies and a closed vertical position for operation of the dies. A drop latch 38 is pivoted to the door 37 near the free edge of the latter and has a shoulder 39 for engaging an abutment 40 on the base 5. A handle 41 on latch 38 provides for manually raising the latter to disengage the shoulder 39 and abutment 40, when it is desired to drop the door 37 to horizontal position. The door 37 has a gate 42 through which the end of wedge member 20 freely extends.

The blank 11 is supported centrally of the dies when first inserted in the press, by a pair of spring pressed lever arms 43 pivoted on brackets 44 on the wear plates 9 and extending upwardly into engagement with the lower edge of the blank. The forward support arm 43 has a roller 45 at its upper end for engaging the blank and allowing freedom of movement of the lever arm along the blank when the latter is expanded downwardly. A stop 46 is provided on the lower end of each lever 43 to limit the upward position of the lever arm when there is no blank 11 in the press.

In operation the punch 6 is raised to its upper position with wedge member 20 withdrawn to the rear to contract mandrel 19 and with the dies 7 and 8 biased outwardly by springs 15. The latch 38 is disengaged and trap door 37 dropped to horizontal position. The blank 11 is then inserted over the mandrel 19 and the trap door 37 closed and secured by dropping latch 38 against abutment 40. Then the punch 6 is lowered. As the side members 14 engage and wedge dies 7 and 8 inwardly toward one another the link 28 pushes block 27 down the inclined surface 24 in groove 25 and thereby forces the wedge member 20 forwardly between mandrel edges 21 and 22, spreading the latter apart vertically.

Thus, as the dies 7 and 8 press the sides of blank 11 inwardly, the edges 21 and 22 of man-

drel 19 spread the blank vertically until it fills the recesses in the dies. The spreading pressure of the mandrel on the blank 11 should exceed the collapsing pressure of the dies thereon so that the forming results primarily from a stretching of the blank as distinguished from a collapsing of the same. The design of the machine may even provide for a sequence of operation wherein the dies 7 and 8 do not close upon the blank until the mandrel 19 has fully or nearly completely expanded the blank vertically. In this way there is less friction between the blank and dies and the latter serve to coin the final shape of the blank.

After forming of the blank the punch 6 is lifted, thereby retracting the member 20 and loosening the mandrel 19, and at the same time allowing the dies to be separated by the biasing action of springs 15. The latch 38 is then released and door 37 dropped. The formed blank can then be removed.

In the forming of a propeller blade tip, it is preferable to employ two separate flattening steps in addition to a pre-spreading step. In carrying these flattening steps out, two separate flattening presses are employed, one only partially flattening the blank, and the other completing the flattening to final propeller size and shape.

The invention may have various embodiments within the scope of the accompanying claims.

I claim:

1. In a press, a pair of platens relatively movable toward and away from each other, a mandrel supported by one of said platens for holding a blank therebetween, said mandrel having at least two longitudinally tapered members disposed for enlargement in one direction by relative longitudinal movement therebetween, means operated by the closing of the platens toward one another to effect relative longitudinal movement between the tapered mandrel parts tending to expand the mandrel, said means comprising a cam surface guide member secured to the platen supporting the mandrel, and a slide block engaging said guide and linked to one of said mandrel parts and to the other platen.

2. In a press, a pair of platens relatively movable toward and away from each other, a mandrel therebetween and having a central longitudinal wedge member disposed between blank engaging members to separate the same and spread the blank when the wedge member is moved inwardly of the mandrel in a direction at an angle to the direction of relative movement of said platens, and means to operate said mandrel wedge member in response to relative movement of said platens, said means comprising a cam member disposed at an angle between said platens and held by one of said platens, and a cam follower therefor linked to said central wedge member and to the other platen.

3. In a press, a pair of platens relatively movable toward and away from each other, a mandrel therebetween and having a central longitudinal wedge member disposed between blank engaging members to separate the same and spread the blank when the wedge member is moved inwardly of the mandrel in a direction at an angle to the direction of relative movement of said platens, means to operate said mandrel wedge member in response to relative movement of said platens, a pair of dies on either side of said mandrel, and means to move said dies toward one another to

compress the blank therebetween in response to relative movement of said platens toward one another, said mandrel operating means comprising a cam member disposed at one end of the dies at an angle to the direction of relative movement of the platens and held by one of said platens, and a cam follower therefor linked to said central wedge member and to the other platen.

4. In a press, a pair of platens relatively movable toward and away from each other, a mandrel disposed therebetween with its axis at substantially right angles to the direction of relative movement between said platens and having a plurality of longitudinal members at least one of which is tapered to effect enlargement of the mandrel by wedging action upon movement of the tapered member, means to operate said mandrel wedge member in response to relative movement of said platens, a pair of dies on either side of said mandrel, means to move said dies toward one another in a direction substantially at right angles to the axis of the mandrel and to the direction of relative movement between said platens to compress the blank therebetween in coordinated response to relative movement of said platens toward one another, and means to secure said blank upon said mandrel and in alignment with the dies, said first named means comprising cam members disposed between said platens and secured and held by one thereof, and a cam follower carried by the other of said platens and linked to said wedge member to operate the latter.

5. In a press, a pair of platens relatively movable toward and away from each other, a mandrel disposed with its axis at right angles to the direction of relative movement between the platens for holding a blank therebetween, said mandrel having a plurality of longitudinal members at least one of which is tapered to effect enlargement of the mandrel by wedging action upon longitudinal movement of the tapered member, a cam track carried by one of said platens having a forward cam guide surface and a reverse cam guide surface, a cam follower carried by the other of said platens and disposed between said cam guide surfaces to respond to the forward cam guide surface as one platen moves relatively toward the other and to the reverse cam guide surface as one platen moves relatively away from the other, and means connecting said cam fol-

lower to said tapered mandrel member to effect forward and reverse movements of the member correlated to the corresponding movements of the follower.

5 6. In a press, a pair of platens relatively movable toward and away from each other, a mandrel carried by one of said platens and disposed with its axis at right angles to the direction of relative movement between the platens for holding a blank therebetween, said mandrel having a plurality of longitudinal members at least one of which is tapered to effect enlargement of the mandrel by wedging action upon longitudinal movement of the tapered member, a cam track carried by one of said platens having a forward cam guide surface and a reverse cam guide surface, a cam follower carried by the other of said platens and disposed between said cam guide surfaces to respond to the forward cam guide surface as one platen moves relatively toward the other and to the reverse cam guide surface as one platen moves relatively away from the other, means connecting said cam follower to said tapered mandrel member to effect forward and reverse movements 10 of the members correlated to the corresponding movements of the follower, a pair of laterally movable dies carried by the platen which supports the mandrel, said dies being adapted to move toward each other to form a blank on said mandrel, and cam means carried by the other platen disposed to engage said dies and to effect inward movement of the same in correlation to the operative movements of said mandrel.
